INVENTOR

Leonard F. Griffin
By his Attorney,
Keweenaw Howard

UNITED STATES PATENT OFFICE.

LEONARD F. GRIFFIN, OF BINGHAMTON, NEW YORK, ASSIGNOR TO UNITED SHOE MACHINERY CORPORATION, OF PATERSON, NEW JERSEY, A CORPORATION OF NEW JERSEY.

MACHINE FOR AND METHODS OF SHAPING UPPERS.

Application filed August 5, 1921. Serial No. 490,072.

To all whom it may concern:

Be it known that I, LEONARD F. GRIFFIN, a citizen of the United States, residing at Binghamton, in the county of Broome and State of New York, have invented certain Improvements in Machines for and Methods of Shaping Uppers, of which the following description, in connection with the accompanying drawings, is a specification, like reference characters on the drawings indicating like parts in the several figures.

This invention relates to methods of working the uppers of boots and shoes over their lasts and to machines by the aid of which the illustrated method may be practiced. For the purpose of explanation the invention is herein shown and described as embodied in and practiced in the use of mechanism applied to a lasting machine of the bed type, an example of which is disclosed in United States Letters Patent No. 1,018,477 granted February 27, 1912, on application of Matthias Brock.

An object of the invention is to position, form, shape or mold the excess portion of the margin of the upper, particularly at the toe, in an upstanding relation to the sole to facilitate the removal of said excess portion in the upper trimming operation.

In accordance with this object the invention provides for engaging the opposite faces of the portion of a lasted shoe upper which extends above the innersole rib and applying pressure thereto to cause it to be molded and set in an upstanding relation to the shoe bottom and substantially over the rib so that it may be readily engaged and trimmed off by upper trimming instrumentalities.

Since this preparation of the excess portion of the upper for trimming must be effected after the lasting operation and prior to the trimming operation, which is next in order, it is desirable to prepare the upper for trimming in conjunction with the lasting operation. Accordingly the invention further provides for shaping the upper into the angle between the feather and rib of the innersole, and, in conjunction with said shaping, applying pressure to the opposite faces of the portion of the upper extending above the rib. As shown herein the upper pressing or molding means consists in members having co-operating surfaces mounted respectively on the hold-down or

rib support and on the wiper by which the upper is shaped into the angle between the feather and the rib, said surfaces being constructed and arranged to come into effective engagement with the upper after the movement of the wiper inwardly is nearly completed.

These and other features of the invention will appear more fully from the following detailed description when read in connection with the accompanying drawings and will be pointed out in the appended claims.

In the drawings,

Fig. 1 is a perspective view of the hold-down and wipers of a bed lasting machine equipped for practicing the method of the present invention.

Fig. 2 is a longitudinal section of the parts shown in Fig. 1, and

Fig. 3 is a transverse section on the line 3—3 of Fig. 2.

In the drawings, the numeral 2 indicates the last, 4 an innersole upon the last bottom, 6 the rib of the innersole, 8 the feather of the innersole, 10 the upper, and 12 the excess portion of the upper which is to be treated.

The usual wipers of a bed lasting machine are indicated at 20, 22, it being understood, of course, that the machine is provided with the usual mechanism for moving the wipers vertically to upwipe the upper about the toe of the last and for closing the wipers to force the upper into the angle between the feather 8 and the rib 6. To support the rib against the action of the wipers a hold-down member formed as a plate or block 24 is provided which is pivoted at 26 to one end of a hold-down finger 28 the opposite end of which is suitably held by a hold-down arm 30. The member or block 24, beside having a face 32 to provide a support for the rib about the end of the toe, has a face 34 formed by extending the member 24, for instance, as far above the top of the rib as it extends below it. This face 34 is preferably located substantially in the plane of the rib, that is, in line with the direction of extent of the rib upwardly from the sole bottom. As shown, said face may be inclined slightly inwardly at the toe end (Fig. 2) and outwardly at the sides of the toe (Fig. 3). To co-operate with the face 34 in treating the excess portion of the upper material extending above the rib 6

there is provided on each of the wipers a pressure member 36. These members are firmly secured to the wipers and have acting faces 38 contoured to correspond to the 5 face 34 of the block 26 and so located that they press the upper firmly against the face 34 when the wipers have seated the upper into the angle between the rib 6 and the feather 8 at the completion of the lasting 10 operation. As a result the excess of upper material, particularly the fulled or bunched portion at the toe of the shoe, is molded in a predetermined upstanding position corresponding substantially to the direction of 15 upward extent of the rib, that is, the upper is molded in the plane of the rib extended above the rib.

The block 26 is provided with a handle 40. In case the block 26 does not move upon its 20 pivot when brought against the rib properly to engage the rib at all points, the handle 40 may be manipulated to secure such proper engagement.

Having thus described my invention, 25 what I claim as new and desire to secure by Letters Patent of the United States is:

1. That improvement in methods of shaping uppers which consists in lasting the upper to a ribbed innersole, and then molding 30 the margin of the upper extending above the rib into an upstanding flange for convenient removal in the upper trimming operation.

2. That improvement in methods of shaping uppers to their lasts which consists in 35 conforming the margin of the upper to the feather and outer face of the rib of an innersole, and then molding the margin of the upper extending above the rib into an upstanding flange for convenient removal 40 in the upper trimming operation.

3. That improvement in methods of shaping the uppers of boots and shoes which consists in supporting the inner face of the rib of an innersole, shaping the upper against 45 the outer face of said rib, and molding the margin of the upper extending beyond the rib into an upstanding position to facilitate removal of said margin in the upper trimming operation.

50 4. That improvement in methods of shaping the uppers of boots and shoes which consists in supporting the inner face of the rib of an innersole, lasting the upper against the outer face of said rib, and molding the 55 margin of the upper extending beyond the rib in an upstanding position substantially perpendicular to the shoe bottom and conforming to the contour of the rib to facilitate removal of said margin in the upper 60 trimming operation.

5. In a machine of the class described, the 65 combination of means for laying the margin of an upper inwardly over the feather of the sole of a shoe on a last, an upper engaging device arranged to be positioned on the sole

and having a face to extend above the inner-
sole rib about the toe end of the shoe, and
means on the overlaying means arranged to
engage the margin of the upper opposite to
said face and to act after the overlaying op- 70
eration to force the upper against said face
and mold it into an upwardly extending
marginal flange for convenient removal in
the upper trimming operation.

6. In a machine of the class described, the 75 combination of means for engaging the op-
posite faces of the margin of a lasted shoe
upper which extends above the innersole
rib, and means for relatively moving the up-
per engaging means to apply pressure to the 80
upper and cause it to be molded and set in
an upstanding relation to the shoe bottom
and substantially above the rib so that it
may be conveniently removed in the upper 85
trimming operation.

7. In a machine of the class described, the
combination of means for supporting the in-
ner face of the rib of an innersole, means for
shaping an upper against the outer face of 90
said rib, and means molding the margin of
the upper extending beyond the rib into an
upstanding position to facilitate removal
of said margin in the upper trimming op-
eration.

8. In a machine of the class described, the 95 combination of means for forming an up-
per into the angle between the feather and
rib of an innersole, and means acting in
conjunction with said forming means to
apply pressure to the opposite faces of the 100
margin of the upper extending above the
rib.

9. In a machine of the class described, 105
the combination of a pair of wipers con-
structed and arranged to wipe the upper of
a shoe over the feather of the innersole and
against the outer face of the innersole rib,
means for supporting the rib against the 110
action of the wipers, pressure applying
means operated by the wipers to engage the
margin of the upper extending above the
rib, and means engaging the inner face of
the upper above the rib and co-operating
with the pressure applying means to mold 115
the margin of the upper into an upstanding
position.

10. In a machine for lasting shoes, the
combination of a holdown member con-
structed and arranged to fit the contour of
the inner face of the innersole rib and hav- 120
ing a portion extending above the rib, wiper-
ers constructed and arranged to wipe the
upper over the feather of the innersole and
against the supported rib, and means on
the wipers for forcing the margin of the 125
upper against the portion of the holdown
member extending above the rib to form
said margin in an upstanding position and
facilitate its being trimmed off in the upper
trimming operation.

11. In a machine of the class described, the combination of a member constructed and arranged to engage the bottom of an innersole upon a last and having an upper 5 engaging face above the plane of the innersole rib of substantially the contour of the rib, and means co-operating with said contoured face to force the upper against said face and form the excess of upper margin in an upstanding position to facilitate the trimming off of said excess.
12. In a machine for lasting shoes, the combination of a holddown member constructed and arranged to fit the contour of 15 the inner face of the innersole rib to support the rib and the margin of upper extending above the rib, wipers constructed and arranged to wipe the upper over the feather of the innersole and against the supported rib, and means on the wipers for molding the margin of the upper extending above the rib against the holddown member in an upstanding position to facilitate its being trimmed off in the upper trimming 25 operation.
13. In a machine for lasting shoes, the combination of a member constructed and arranged to engage the bottom of an innersole upon a last and having an upper engaging face extending above the plane of the innersole rib in the plane of the rib extended and having substantially the contour of the rib, and means co-operating with said extended and contoured face to force the 35 upper against said face and form the excess of upper margin extending above the rib in an upstanding position to facilitate the trimming off of said excess.
14. In a machine of the class described, the combination of means for laying the 40 margin of an upper inwardly over the margin of the sole of a shoe on a last, an upper engaging device arranged to be positioned on the sole and having a face to extend above the sole about the toe end of the 45 shoe, and means on the overlaying means arranged to engage the margin of the upper opposite to said face and to act after the overlaying operation to force the upper against said face and mold it into a marginal flange substantially perpendicular to the shoe bottom for convenient removal in the upper trimming operation.
15. In a machine of the class described, the combination of wipers for wiping an 55 upper into the angle between the feather and rib of an innersole, means for supporting the rib and for holding the portion of upper extending above the rib in the plane of the rib extended, and blocks on the wipers shaped to correspond to the upwardly extending portion and co-operating therewith to compress the portion of the upper above the rib and set it in condition to facilitate the trimming off of the excess portion 60 of the upper.

In testimony whereof I have signed my name to this specification.

LEONARD F. GRIFFIN.
